US0D1088363S

(12) **United States Design Patent** (10) **Patent No.:** **US D1,088,363 S**
(45) **Date of Patent:** **** Aug. 12, 2025**

(54) **BEE HIVE BASE**

(71) Applicant: **Australian Honeybee Pty Ltd**,
Mitchell (AU)

(72) Inventors: **Victor Croker**, Mitchell (AU); **David Leemhuis**, Mitchell (AU); **Jonathan Dyer**, Mitchell (AU)

(73) Assignee: **Australian Honeybee Pty Ltd**,
Mitchell (AU)

(**) Term: **15 Years**

(21) Appl. No.: **29/849,961**

(22) Filed: **Aug. 16, 2022**

(30) **Foreign Application Priority Data**

Feb. 18, 2022 (AU) 202210942

(51) **LOC (15) Cl.** **30-02**

(52) **U.S. Cl.**

USPC **D30/120**

(57) **CLAIM**

The ornamental design for a bee hive base as shown and
described.

DESCRIPTION

FIG. 1 is a front, top, left side, isometric perspective view of
a bee hive base in accordance with our design;

FIG. 2 is a front, bottom, right side, isometric perspective
view of the bee hive base of FIG. 1;

FIG. 3 is a front elevation view of the bee hive base of FIG.
1;

FIG. 4 is a rear elevation view of the bee hive base of FIG.
1;

FIG. 5 is a top plan view of the bee hive base of FIG. 1;

FIG. 6 is a bottom plan view of the bee hive base of FIG. 1;

FIG. 7 is a left side elevation view of the bee hive base of

FIG. 1; and,

FIG. 8 is a right side elevation view of the bee hive base of

FIG. 1.
